(57) **CLAIM**

The ornamental design for an automotive fluid tank, as shown and described.

DESCRIPTION

FIG. 1 is a perspective view of an automotive fluid tank showing our new design;

FIG. 2 is a top plan view of the automotive fluid tank of FIG. 1;

FIG. 3 is a bottom plan view of the automotive fluid tank of FIG. 1;

FIG. 4 is a right side elevational view of the automotive fluid tank of FIG. 1;

FIG. 5 is a left side elevational view of the automotive fluid tank of FIG. 1;

FIG. 6 is a front elevational view of the automotive fluid tank of FIG. 1; and,

FIG. 7 is a rear elevational view of the automotive fluid tank of FIG. 1.

The portions shown in broken lines are included for illustrative purposes only and form no part of the claimed design.
